DESIGN FOR A SOAP DOLL

Florence N. Lewis, New York, N. Y.

Application November 12, 1938, Serial No. 81,043

Term of patent 3½ years

To all whom it may concern:

Be it known that I, Florence N. Lewis, a citizen of the United States, residing at New York, in the county of New York and State of New York, have invented a new, original, and ornamental Design for a Soap Doll, of which the following is a specification, reference being had to the accompanying drawing, forming part thereof.

In the drawing:

Fig. 1 is a front view of a soap doll showing my new design;

Fig. 2 is a side view thereof.

Fig. 3 is a bottom view.

I claim:

The ornamental design for a soap doll, as shown.

FLORENCE N. LEWIS.
